UNITED STATES PATENT OFFICE.

WILLIAM NELSON BRUCE, OF HOLLISTER, CALIFORNIA.

PIPE WRENCH AND CUTTER.

1,165,649.

Specification of Letters Patent.

Patented Dec. 28, 1915.

Application filed September 20, 1915. Serial No. 51,657.

To all whom it may concern:

Be it known that I, WILLIAM N. BRUCE, a citizen of the United States, residing at Hollister, in the county of San Benito and 5 State of California, have invented a new and useful Pipe Wrench and Cutter, of which the following is a specification.

The present invention relates to pipe wrenches and cutters, and aims to provide a 10 novel and improved device of that character.

It is the object of the invention to provide a pipe wrench of the chain type so constructed that the wrench may be employed upon various sizes of pipes or equivalent objects 15 with equal success and propriety, the handle or lever having novel means for the adjustable engagement of the chain, and a pipe-engaging member connecting one end of the chain and the end of the handle or lever, said 20 member being adapted to bear against the pipe when the device is used as a wrench, and having a cutter to sever the pipe when the device is used as a pipe cutter. In other words, interchangeable elements are employed for connecting the handle or lever and chain, one of said elements being adapted 25 for use when the device is employed as a wrench, the other element being adapted for use when the device is employed as a pipe 30 cutter.

It is also within the scope of the invention to provide a device of the character specified which is exceedingly simple, light, strong, and inexpensive in construction, and which 35 is durable, serviceable, practical, efficient and convenient in use.

With the foregoing and other objects in view which will appear as the description proceeds, the invention resides in the combination and arrangement of parts and in the 40 details of construction hereinafter described and claimed, it being understood that changes in the precise embodiment of the invention herein disclosed can be made within 45 the scope of what is claimed without departing from the spirit of the invention.

The invention is illustrated in the accompanying drawing, wherein:—

Figure 1 is a side elevation of the device 50 used as a wrench, a portion of the handle or lever being broken away. Figs. 2, 3 and 4 are enlarged sectional details taken on the lines 2—2, 3—3 and 4—4, respectively, of Fig. 1. Fig. 5 is an enlarged inside view of 55 one arm of the fork. Fig. 6 is a fragmental

side elevation of the device used as a pipe cutter, a portion of the handle or lever being broken away. Fig. 7 is an enlarged perspective view of the cutting blade employed when the device is used as a pipe cutter. 60

In carrying out the invention, there is employed a handle or lever 1 of any suitable length, and provided at one end with a fork 2, the arms or prongs of which are provided upon their inner or adjacent sides and adjacent their free ends with bosses or abutments 3 projecting toward and facing one another. The free ends of the fork arms are provided with apertures 4 which also extend through the bosses 3, and the inner or adjacent sides of the fork arms are also provided with step portions 5 between the bosses 3 and the body portions of said fork arms, the faces of the portions 5 being disposed in planes between the planes in which the faces 75 of the bosses 3 and the inner sides of the fork arms lie. The portions 5 are each provided with a pair of opposite recesses 6 whose remote walls are flush with the inner sides of the fork arms, and said recesses 80 provide lugs 7 therebetween.

A curved shoe 8 adapted to rest against or bear upon the pipe or equivalent object is provided between its edges with an outstanding flange 9 one end of which is disposed between the bosses 3. A bolt or pivot element 10 is engaged through the bosses 3 and flange 9, and one end of a chain 11 is pivotally anchored to the other end of the flange 9, said member 8 serving to connect 90 the respective ends of the chain and lever. This member 8 is of T-shaped cross section. 85

The chain 11 embodies the pairs of outer links 12, and pairs of inner links 13, the links being of panduriform contour, and 95 having their ends overlapped and pivotally connected by means of rivets or pins 14 which have their ends protruding. The pair of links 12 at one end of the chain straddle the respective end of the flange 9 and are 100 pivoted thereto by means of a bolt or pivot element 15. The free portion of the chain is adapted to pass snugly through the fork, the ends of the rivets or pins 14 being adapted to snugly engage the inner or adjacent 105 sides of the fork arms.

In using the device as a pipe wrench, after the member 8 is placed against the pipe, the chain is passed around the pipe and the free portion of the chain is then pushed through 110

the fork 2. The chain is then pulled as tight as possible, the lever 1 being swung to the left, as viewed in Fig. 1, so that the recesses 6 can receive the proper rivets or pins 14, with one of the pins bearing against the lugs 7. Then, when the lever 1 is swung in the other direction, toward the right as viewed in Fig. 1, the chain is tightened about the pipe whereby the pipe will be gripped to thus rotate or turn with the lever. By swinging the lever toward the left, as seen in Fig. 1, the chain can again be released and moved upon the pipe to enable a new hold to be obtained. The chain, although it can effectively grip the pipe, is not liable to cut, crush or otherwise injure the pipe. The chain 11 may be adjusted readily relative to the lever 1 for accommodating various diameters of pipes, and the links 20 of the chain fit snugly between the portions 5, as seen in Fig. 2.

When the device is used as a pipe cutter, the member 8 is replaced by a link 9' having a lobe-shaped cutter blade 8' whose edge is sharpened. The blade 8' is located adjacent one end of the link 9', and said end of the link is adapted to pivotally engage the bolt 10 between the bosses 3, while the respective end of the chain 11 is connected by means of the bolt 15 to the other end of the link 9'. Then, when lever is manipulated, the cutter blade 8' may be forcibly thrust through the walls of the pipe, and by oscillating the lever and shifting the chain around the pipe, the pipe 35 can be cut by a single revolution of the device around the pipe.

The members 8 and 8' can be used interchangeably for connecting the lever and

chain, to enable the device to be used either as a pipe wrench or pipe cutter.

Since the recesses 6 are provided at the opposite edges of the fork arms, the lever 1 can be reversed, so that the lever can be used in either position.

Having thus described the invention, what is claimed as new is:

1. In a device of the character described, a lever, a chain, the lever having means for the adjustable engagement of the chain, and a link connecting the chain and lever and having a cutter blade projecting therefrom to cut the pipe to which the chain is applied.

2. In a device of the character described, a lever having a fork at one end whose arms are provided at their free ends with bosses 55 projecting toward one another, the adjacent sides of the fork arms having step portions between said bosses and body portions of the arms, a pivot element engaged through said bosses, and a chain having one end pivotally 60 anchored to said pivot element, the chain embodying links and pins pivotally connecting them, the pins having protruding ends, and said step portions of the fork arms having recesses for receiving the protruding 65 ends of said pins and providing lugs between said recesses for the engagement of said pins.

In testimony that I claim the foregoing as my own, I have hereto affixed my signature 70 in the presence of two witnesses.

WILLIAM NELSON BRUCE.
